Primary Examiner — Jennifer L Rempfer*(74) Attorney, Agent, or Firm* — Osha Liang LLP(57) **CLAIM**

The ornamental design for a scraper for removing fish entrails, as shown and described.

DESCRIPTION

1.1 shows a front view of a scraper for removing fish entrails;

1.2 shows a back view of a scraper for removing fish entrails;

1.3 shows a right view of a scraper for removing fish entrails;

1.4 shows a left view of a scraper for removing fish entrails;

1.5 shows a top view of a scraper for removing fish entrails;

1.6 shows a bottom view of a scraper for removing fish entrails;

1.7 shows a perspective view of a scraper for removing fish entrails;

1.8 shows a perspective view of a scraper for removing fish entrails;

1.9 shows a left view of a scraper for removing fish entrails in an environment of use;

1.10 shows an end view of a scraper for removing fish entrails in an environment of use;

1.11 shows another end view of a scraper for removing fish entrails in an environment of use;

1.12 shows another end view of a scraper for removing fish entrails in an environment of use; and

1.13 shows another end view of a scraper for removing fish entrails in an environment of use.

The elements shown in broken lines are for illustrative purposes only and form no part of the claimed invention.
